CLAIM

The ornamental design for a hand mixer, as shown and described.

DESCRIPTION

FIG. 1 is a top, front, left side perspective view of a hand mixer, showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown across the surfaces in FIGS. 1-7 show unclaimed seam lines of the hand mixer and form no part of the claimed design.

The dot-dash broken lines of FIGS. 1-7 immediately adjacent to the claimed areas represent the boundaries of the design and form no part thereof.

None of the broken lines form any part of the claimed design.
